UNITED STATES PATENT OFFICE.

LEON FREEMAN, OF CHICAGO, ILLINOIS.

HAT AND HAT-LINING.

1,275,238.

Specification of Letters Patent. Patented Aug. 13, 1918.

Application filed December 29, 1917. Serial No. 209,382.

To all whom it may concern:

Be it known that I, LEON FREEMAN, a citizen of the United States, and a resident of Chicago, in the county of Cook and State of Illinois, have invented certain new and useful Improvements in Hats and Hat-Linings, of which the following is a specification.

My invention relates to hats such as are worn upon the head. It has more particular reference at the present time to ladies' hats.

The manufacturer of ladies' hats usually provides in the hat a lining which comprises a band-like portion or "side" stitched about the head opening of the crown, and an upper portion or "tip" stitched about the gathered or Shirred upper edge of the side. The shirring of the upper portion of the side causes the lining to conform somewhat to the general shape of the crown and leaves an opening ordinarily from four to five inches in diameter, or of oval shape. The tip is permanently stitched to the shirred edge of the side, thus making a complete cup-shaped lining for the hat. The lining is first made complete and later stitched about the margin of the head opening of the crown of the hat.

The manufacturer also frequently applies various kinds of trimming to the hat, such as ribbon bands, bows, artificial foliage, etc. Sometimes the retailer of the hat applies the trimmings, and sometimes the purchaser of the bare "shape" with the lining secured thereto applies the trimmings at home. It often happens that the trimmings applied by the manufacturer or by the retailer do not suit the customer, although the shape of the hat is satisfactory. In such cases the common practice is to rearrange the old or apply new trimmings to suit the customer. Frequently, too, during the life of the hat the owner desires to rearrange the trimmings from time to time or to apply different trimmings. Whenever in a hat of the construction indicated it is desirable to rearrange or apply new trimmings to a shape it is nearly always necessary to take out the lining, which is done by breaking the stitches here and there at the place where the lining is secured to the shape, and after the repairs or alterations have been made the lining must be replaced. Such operations consume a considerable amount of time and are expensive to the dealers and, when done by the

wearer, unnecessarily bothersome and annoying, as indicated by the improvements herein disclosed.

In view of the foregoing disadvantages inhering in the usual hat and lining construction heretofore, the object of the present improvements is to provide a hat lining having provisions whereby when the same is in normal position in the hat, access may be had to the interior surfaces of the crown for alterations or repairs to the ornamental trimmings, or for any other purpose, in an easy and expeditious manner, and without the necessity of separating the side portion of the lining from the hat.

In the accompanying drawings, which form a part of this specification, I have illustrated these improvements as applied to a hat of conventional outline. In these drawings Figure 1 is a medial, longitudinal, vertical section through the hat and lining;

Fig. 2 is a fragmentary bottom view of the hat of Fig. 1 with a portion of the lining side broken away to show otherwise concealed parts;

Fig. 3 is a face view of the tip of the lining; and

Fig. 4 is a fragmentary sectional view showing the preferred form of catch means for holding the tip upon the side.

The hat may be of any approved shape, form or material. It is shown as comprising a crown portion 10 and a brim 11. The side portion or side 12 of the lining may be of the usual construction and is made from a strip of fabric of the desired width, which width may vary according to the height of the crown, but which will be sufficient to admit the head of the wearer into the crown as far as may be desired. About five inches is perhaps the more usual width for the strip constituting the side 12. The upper edge of the side 12 is shown as being turned over at 13 forming a hem to give finish and to provide a better foundation for the fasteners. The upper portion of the side is gathered or shirred as usual so as to draw the opposite portions of the edge 13 somewhat together, thus leaving an opening 14, which may be circular or oval as desired, and which is shown as oval or elliptical in the drawings.

I also provide a tip 15, which is preferably a rectangular piece of fabric, as well shown in Fig. 3, but which may conform in outline more accurately to the shape of the

opening 14 if desired, being preferably somewhat larger than the opening 14. By making the tip portion 15 rectangular the corners thereof substantially deeply overlap the upper portion of the side and assist in holding the tip in its desired position when in use.

Around the margin of the edge 13 of the side I provide catch or locking elements 17, 10 and at corresponding distances apart and in the same arrangement I provide on the tip 15 interlocking elements 18 adapted to engage the elements 17 in readily removable relation. I preferably employ the well known form of snap catch illustrated having a head on one member adapted to be sprung into a socket on the other member, which form of snap catch requires no detailed description. Other forms of interhooking or 20 interlocking devices of a readily operable character to release one part from the other may be employed.

In practice the improved lining is stitched in its desired position according to the older practice, namely, along the edge 20, at or adjacent to the head opening of the hat. Suitable ornamentation may also be applied to the outside of the hat by the manufacturer or dealer at any time either before or 25 after the side 12 has been secured by stitching, as at 20. Should alterations, modifications or repairs be required at any time, before or after the hat goes into the possession of the wearer, access may be had to the 30 interior of the crown by simply releasing some or all of the catch elements 17 and 18

from each other, thus constituting the opening 14 between the edges 13 a hand opening for the person making the substitutions, alterations, or repairs. Ordinarily for such operations the improved lining will be drawn bodily out of the crown and the tip 15 entirely removed, whereupon the hand may be inserted into the crown of the hat for manipulating the needle or doing any other necessary work.

Having finished the repairs it is only necessary to reengage the catch members 17 and 18 and push the lining back into position.

I claim:

1. A hat lining comprising in combination a part having a hand opening therein, catch elements spaced apart about said opening, a closure for said opening, catch elements 55 spaced apart on said closure and adapted to coöperate with said first mentioned catch elements for holding the closure in closing position on said part having the opening, said catch elements being readily operable 60 to release said closure to admit the hand to be passed through said opening.

2. A hat lining comprising in combination a side portion, a tip portion, and a plurality of spaced apart readily releasable interlocking catches positioned operatively between the tip portion and the side portion to hold the two portions in readily separable relation to each other, each of said catches comprising a pair of co-engaging members.

LEON FREEMAN.
